UNITED STATES PATENT OFFICE

RALPH R. WOLTSTEM, OF OZONE PARK, NEW YORK

BREAST SUPPORTER

Application filed June 16, 1928. Serial No. 286,050.

This invention relates to new and useful improvements in breast supporters for women and aims to provide simple, inexpensive and efficient means whereby large and flabby breasts of women, especially of the buxom type, may be so supported as to assume a firm and solid condition. Furthermore, the use of my present device will prevent the flapping of the breasts while walking, which always is an undesired feature in women afflicted with breasts of unusual proportions.

In carrying out this invention, I make provision of the well known corset, girdle or other form sustaining garment to serve as a means for carrying the breast supporters, which are in the form of a pair of stems movably associated with socket members associated with the garment at the upper edge thereof and directly beneath the breasts, said stems being formed or equipped at their upper ends with brackets suitably shaped to conform to the curvature of the undersides of the breasts. Furthermore, spring means is provided for normally urging the stems in an upward direction. The spring means is however, of such a nature as to permit the stems to move downwardly when the user of the support bends over, so that the brackets will not bind, and thus produce discomfort.

An essential object of this invention is to provide a supporter of this character that is simple and inexpensive, and that is highly serviceable, as well as comfortable, and that will perform all of the functions heretofore stated.

With the foregoing and other objects in view as the nature of the invention is better understood from the following specification when considered in accompaniment with the drawings, wherein like reference characters indicate corresponding parts throughout the views:

Figure 1 is a fragmentary front elevation of a female wearing a corset equipped with my breast supporters.

Figure 2 is a side elevation thereof.

Figure 3 is a fragmentary front elevation of the corset so equipped.

Figure 4 is a vertical section through one

of the socket members associated with the garment and within which is arranged one of said stems.

Figure 5 is a vertical section taken at right angles to Figure 4.

Figure 6 is a group perspective of the two units forming one of the said sockets.

Figure 7 is a transverse section therethrough, and

Figures 7A, 8 and 9 are elevations of different types of breast engaging brackets associated with the upper ends of the stem members.

Now having particular reference to the drawings, A designates a corset, girdle or other form retaining garment usually worn by females. Associated with the garment at the upper edge thereof, and at opposite sides of the center directly beneath the breasts of the wearer are vertically arranged socket units 5—5. These socket units are of any required dimensions, and preferably of relatively flat formation. They may be of any required construction, each preferably consisting of a backing plate 6 having perforations 7 at their edges to facilitate the stitching thereof to the garment. Furthermore, at each vertical edge of the plate as well as at the lower edge are slots 8, while for association with the plate is a narrower keeper plate 9 having inturned flanges 10 at its vertical and lower edges, these flanges being equipped with inwardly projecting tongues 11 for engagement through the plate slots 8, after which they are turned inwardly as disclosed in Figure 7 to lock the keeper to the backing plate 6. Secured at its lower end within the bottom of each socket unit 5 is an expansible flat coiled spring 12, the strength of which is slightly greater than the particular breast being supported. Freely vertically movable within each socket member is a flat strip stem 13 of any desired material, and of a predetermined length. Formed or otherwise associated with the upper end of each stem 13 is a bracket 14 bent slightly forwardly and of a contour conforming to the contour of the underside of the breast; see Figures 1, 2 and

5. These brackets may be of any desired de-

sign, such as shown in Figures 1 to 5, or as in Figures 7 to 9.

Obviously, when the garment A is arranged upon the body, the stems 13 are forced downwardly against the action of their respective springs. The brackets at the upper ends of these stems are then properly arranged beneath each breast for obviously supporting the breasts in a firm and relatively forwardly projecting condition.

- 10 In view of the foregoing specification when considered with the accompanying drawings, it will be obvious that I have produced a novel, simple, useful and inexpensive breast support for association with form supporting garments, and even though I have herein shown and described the invention as consisting of certain detailed structural elements, it is nevertheless to be understood that some changes may be made therein, without departing from the spirit and scope of the appended claims.

What I claim as new, and desire to secure by Letters Patent is:

- 25 1. In combination with a waist form retaining garment, means for supporting a woman's breasts in proper position, said means consisting of a pair of brackets, each having a depending arm engageable at its lower end with the garment, said garment having a pair of sockets for receiving the lower ends of said stems and means within the sockets for normally urging the stems in an upward direction.
- 30 2. In combination with a waist form retaining garment, means for supporting the breasts of the woman wearing the garment, said means consisting of a pair of sockets associated with the garment directly beneath the breasts, a pair of stems arranged vertically at their lower ends within the sockets, means at the upper ends of the stems for conforming to the curvature of the adjacent portion of the breasts and means between the sockets and said stems for normally urging the latter in an upward direction.
- 35 3. In a breast supporter of the character described, a keeper unit adapted for attachment to a garment beneath the breast of the wearer, means slidably associated with the keeper and extending vertically therefrom for engagement at its upper end with the underside of the adjacent breast, and means between the keeper and said first mentioned means for normally urging said first mentioned means in an upward direction.

Signed at Jamaica, in the county of Queens and State of New York, this 14th day of June, A. D. 1928.
